UNITED STATES PATENT OFFICE.

WILLIAM A. CRAWFORD-FROST, OF BALTIMORE, MARYLAND.

TORPEDO-OBSTRUCTING PROJECTILE.

1,377,467.

Specification of Letters Patent.

Patented May 10, 1921.

Application filed November 13, 1920. Serial No. 423,980.

To all whom it may concern:

Be it known that I, WILLIAM A. CRAWFORD-FROST, a citizen of the United States of America, residing in the city of Baltimore, in the State of Maryland, have invented certain new and useful Improvements in Torpedo-Obstructing Projectiles, of which the following is a specification, reference being had therein to the accompanying drawings, 10 in such full and clear terms as will enable those skilled in the art to construct and use the same.

This invention relates to projectiles which are shot from a gun to obstruct torpedoes 15 and its chief object is to provide such a projectile as may be easily loaded into the gun and fired therefrom effectively, will expand in the air, and, no matter how it falls into the water, will offer a large surface of net-work in opposition to an oncoming torpedo, 20 and which will cause the course of the torpedo to be altered from a straight to a circular one in case the torpedo hits any part of the net surface.

25 This invention aims to accomplish the above results by a combination of mechanical elements that will be hereinafter specifically described and then claimed, and reference will be had to the drawings, wherein 30 there are illustrated the principles of my invention in which:—

Figure 1 is a plan view of the device as it lies in the water showing the flotation tube and collapsible but not foldable transverse arms, extended, in a position to support respectively the longitudinal or bisecting and transverse or bisected nets.

Fig. 2 is a plan view of the device loaded into the gun, with the nets removed to show 40 how the collapsible arms are held down by a ring around the gun barrel, and how the coil springs and rings for supporting the longitudinal or bisecting net are compressed and pushed forward on the portion of the 45 flotation tube that is outside the gun.

Fig. 3 is a front elevation of the device showing the transverse or bisected net extended and the edge of the longitudinal or bisecting net, also the pointed head of the 50 projectile, arm blocks and arms.

Fig. 4 is a side elevation showing the longitudinal net extended and the edge of the transverse or bisected net, also the flotation tube, rings for supporting the longitudinal

or bisecting net coil springs to space rings 55 apart, projectile head, arm blocks, spring hinges and the ends of the arms.

Further describing my invention with reference to the drawings, like letters denote corresponding parts throughout: B is 60 a flotation tube about twenty to twenty five feet in length, the diameter of which will depend upon the weight of the net it is to support. It may be filled with hydrogen if necessary, or it may not be a tube but a 65 solid wooden log if suitable. The front end of B is fastened into the head A, either by being screwed in or in any other suitable manner. To the sides of the head A are attached, by the powerful spring hinges 70 E and E₁, the arm blocks C and C₁ into which are fastened the arms D and D₁, either by being screwed in or in any other suitable manner. The transverse or bisected net L may be of any suitable size, shape, 75 material or construction and may be attached to the transverse arms D and D₁, either by rings as shown, or by hooks and eyes; or in any other preferred manner. The longitudinal or bisecting net, M, of 80 similar material and construction, is attached preferably by closed hooks to the rings G, G₁, G₂, G₃, G₄, etc., which surround the flotation tube. These rings should be flat and wide enough to prevent 85 rocking and sticking when they are pushed along the tube by the expansion of the coil springs H, H₁, H₂, H₃, H₄, etc., and must be able to slide freely along the tube. I is a retaining ring, surrounding the gun barrel K and fastened to it by the chains J and J₁ to prevent the ring from being 90 dragged off when the gun is fired.

Operation: The gun should be charged with a sufficient quantity of a very slow 95 burning powder. The projectile, with the arms D and D₁ held down by the ring I, is raised to the level of the gun muzzle. Then the rear end of the flotation tube is pressed down into the gun to whatever depth is 100 found to be most effective. As the diameter of the flotation tube B should be a close fit to the caliber of the gun, the muzzle will compress the rings G, G₁, G₂, G₃, G₄, etc., and the coil springs H, H₁, H₂, H₃, H₄, etc., 105 and shove them forward on the flotation tube B. Though these coil springs should be strong enough to extend the longitudinal

net they should not be strong enough to overcome the weight of the whole projectile and will remain compressed on the front part of the flotation tube so long as the rear portion remains in the gun and will not cause the projectile to fly out of the gun. Attach the ring I, by hooks on the ends of the chains J and J₁, either to rings in the sides of the gun or to rings fixed in the deck. The nets can either be lifted off the deck and wrapped loosely around the projectile, or tied beneath it by strings that are strong enough to hold the weight of the nets but are too weak to withstand the upward tension of the arms when they are released and begin to extend. When the shot is fired the arms D and D₁ are drawn through the retaining ring I and the projectile flies out of the gun. So long as the motion of the projectile is rapid the arms remain down, as the pressure of the air neutralizes the upward pressure of the spring hinges E and E₁ so that the strings retain the nets and the projectile has a more or less arrow-like shape, but when the motion of the projectile begins to slacken, the upward pressure of the arms D and D₁ breaks the strings, the transverse net is carried forward and extended and the coil springs H, H₁, H₂, H₃, H₄, etc., on the flotation tube B extend the rings G, G₁, G₂, G₃, G₄, etc., carrying the longitudinal net M along to the full length of the flotation tube. The device expands in the air and falls into the water with both nets extended, and they instantly sink to the perpendicular, being made preferably of metal rings. By having the two nets at right angles to each other there is always a considerable expanse of net surface in opposition to the torpedo, whereas if only a single net were used it might fall parallel with the course of the torpedo and the torpedo would not be likely to strike it. If the torpedo hits the port side of the transverse net, it must swing the torpedo to port, as the whole projectile becomes an impediment on the port side of the torpedo, and must act like a rudder hard-a-port to send the torpedo around in a circle anti-clockwise. If the torpedo should strike the starboard side of the transverse net, it must swing the torpedo to starboard in a circle clockwise. Even if the torpedo should hit the center of the transverse net the flotation tube would guide it to one side or the other. If the torpedo should hit the longitudinal net the transverse arms and the transverse net would be likely to make it turn in their direction. It would be practically impossible for the torpedo to push the projectile straight ahead of it and continue on in a straight course. The motion of the torpedo would be rapidly slowed by having to push such a mass of impedimenta through the water and the circles would be so small

that the torpedo would be rendered practically harmless. If desirable the arms can be made to lock extended.

It is obvious that net-cutting devices on torpedoes would not be as effective against 70 a movable net as against a rigid one, and consequently the nets for such a device as this could be of considerably lighter material than could be used if the nets were rigidly suspended at a distance from a ship 75 to try to stop a torpedo coming through.

Now that a listening device has been invented which enables persons on board ship to hear a torpedo several thousand yards off, the invention of torpedo-obstructing projectiles becomes of tactical significance and practical importance. When an alarm is first sounded if the ship is turned away from the direction of the sound, only the stern or a portion of the hull would require protection, and a few of these nets fired astern would be a safeguard. While the torpedo 80 would be traveling only a small part of the distance mentioned there would be ample time to fill the water behind the ship with 85 so many of these nets that there would be only a small chance of the torpedo getting through. In addition to this the gunners being on the alert would be likely to see the wake and besides firing the nets in a general direction some could be shot directly across the path of the wake, always allowing for the torpedo being about 150 feet ahead of its wake.

It is believed that the manner in which 100 the nets, flotation tube, head, arm blocks, arms, rings, and coil springs coöperate in producing a projectile that will be effective in obstructing torpedoes will be apparent without further description, and while in 105 the drawings there is illustrated a preferred embodiment of the invention, it is to be understood that the structural elements thereof are susceptible to such variations and modifications as fall within the scope of the appended claims.

Having therefore described my invention what I claim as new and desire to secure by Letters Patent of the United States is as follows:—

1. In a torpedo-obstructing projectile the combination of a flotation tube with two transverse arms attached to the front end thereof by arm blocks and spring hinges, said arms, arm blocks, and hinges being at 110 all times outside the flotation tube.
2. In a torpedo-obstructing projectile the combination of two nets at right angles to each other, one bisecting the other.
3. In a torpedo-obstructing projectile the combination of two nets at right angles to each other, one bisecting the other, with a flotation tube supporting the bisecting net and two transverse arms, attached to the front end of the flotation tube by arm blocks 115

and spring hinges outside the flotation tube, said transverse arms supporting the bisected net.

4. In a torpedo-obstructing projectile, the combination of two nets at right angles to each other, one bisecting the other, with a flotation tube supporting the bisecting net; and two transverse arms, attached to the front end of the flotation tube by arm blocks and spring hinges outside the flotation tube, said transverse arms supporting the bisected net; and the bisecting net being supported by rings on the said flotation tube, said rings being spaced apart by coil springs.
- 15 5. In a torpedo-obstructing projectile, the combination of two nets at right angles to each other, one bisecting the other, with a flotation tube supporting the bisecting net; and two transverse arms, attached to the

flotation tube by arm blocks and spring 20 hinges outside the flotation tube, the said transverse arms supporting the bisected net; and the bisecting net being supported by rings on the said flotation tube, the said rings being spaced apart by coil springs; 25 and a ring as shown herein for holding down said transverse arms; and chains having hooks at each end to attach the said ring to a gun, or to a deck of a ship, before firing.

In testimony whereof I have hereunto set 30 my hand this 12th day of November in the year of our Lord one thousand nine hundred and twenty in the presence of the subscribed witnesses.

WILLIAM A. CRAWFORD-FROST.
